UNITED STATES PATENT OFFICE

157,470

GUN-TYPE SOLDERING IRON

Harold W. Darr, Minneapolis, Minn., assignor to
Phillips Manufacturing Company, Inc., Minneapolis, Minn., a corporation of Minnesota

Application September 6, 1949, Serial No. 4,861

Term of patent 14 years

(Cl. D26—1)

To all whom it may concern:

Be it known that I, Harold W. Darr, a citizen of the United States, residing at Minneapolis, in the county of Hennepin and State of Minnesota, have invented a new, original, and ornamental Design for a Gun-Type Soldering Iron, of which the following is a specification, reference being had to the accompanying drawings, forming part thereof.

Referring to the drawings:

Fig. 1 is a top plan view of a gun-type soldering iron, showing my new design;

Fig. 2 is a side elevational view thereof;

Fig. 3 is a bottom plan view;

Fig. 4 is an end elevation as seen from the left to the right with respect to Fig. 2; and

Fig. 5 is an end elevation as seen from the right to the left with respect to Fig. 2.

I claim:

The ornamental design for a gun-type soldering iron, as shown.

HAROLD W. DARR.
